MACHINE FOR TESTING YARN

Johann Paul Laetsch, Zurich, Switzerland

Application December 15, 1933, Serial No. 702,612
In Germany December 22, 1932

12 Claims. (Cl. 265—2)

This invention relates to means for testing the strength and uniformity of yarns by the rupture of pieces of thread of a definite length. By the methods at present usual yarns are tested in such a way that the breaking strength or rupture force is continuously noted, and first the principal mean, that is to say, the mean breaking value is found. In addition to this the percentage deviation of the sub-mean is compared, that is to say, the mean of all those values which are below the principal mean. This furnishes a measure of the quality of the product. This method of measuring, however, only enables a judgment to be formed with difficulty with respect to the behavior of the yarn in its further treatment. In this further treatment the uniformity of the breaking strength is of the utmost importance. A yarn of good average breaking strength may contain individual low breaking values which lead to stoppages during the succeeding operations, whereas a weaker yarn, in which however the breaking values do not differ widely from the principal mean, is greatly to be preferred in this respect.

Appliances for carrying out the testing of yarn, which record breaking values automatically upon strips of paper are already known. They record these, however, only in the time sequence in which they occur. This method of recording does not enable the minimum values to be recognized at first glance. In order to determine the mean breaking force and the mean elongation, a calculation always has to be made. Hence a considerable expenditure of time is required for carrying out the known testing processes, and even then the result may be doubtful owing to errors of calculation. Furthermore only the count before and after the breaking tests can be determined, whereas what is of special importance is the knowledge of the count of the yarn actually broken.

Now the present invention is distinguished by the fact that the breaking values are automatically recorded according to their frequency and their order of magnitude. For this purpose a recording appliance is provided, and also devices which add up and indicate the individual breaking values and elongations.

By this means the minimum breaking values that are unsafe for the further treatment of the thread can be immediately recognized, and the yarn can easily be judged in this particular. For the determination of the mean breaking strength and elongation, calculation is no longer required. This results in a saving of time and in the elimination of a source of error.

The invention further provides an automatic drawing in or feeding and breaking device, which is so designed that the feeding and breaking of two different pieces of thread are effected simul-

taneously. By this arrangement the number of breaking operations per unit of time can be considerably increased as compared with known apparatus.

Finally, the invention also provides a device which collects the broken pieces of thread for the purpose of determining the count of yarn from the weight, and also for determining if desired the percentage of moisture contained therein. In this manner the count of the yarn actually broken is obtained, and therefore the quality of the product tested may be definitely determined with much greater certainty.

One form of construction according to the invention is illustrated by way of example in the accompanying drawings, in which

Figure 1 is a perspective front view of the apparatus according to the invention,

Figure 2 is an end view of details, partly in section,

Figure 3 shows a section on the line III—III in Figure 2,

Figure 4 is a diagram made by the apparatus according to the invention, and

Figure 5 shows further co-operating parts of the apparatus in end elevation, partly in section.

In Figure 1, 1 denotes a shaft driven by a motor, not shown at a uniform speed of revolution, 2 a cylinder mounted on this shaft to rotate therewith and provided with a cam groove, and 3 a slide reciprocated by this cylinder and guided on rods 4 and 5 rigidly mounted in the frame (not shown) of the machine. The slide 3 is connected by a link 6 with a feeding arm 8, which is rockable about a pivot 7 mounted in the frame of the machine. The piece of thread to be broken, which is indicated by 9, is clamped between two rupture clamps 11 and 12, of which the clamp 11 is fitted to the slide 3, and the clamp 12 to a lever 10, hereinafter referred to as the rupture lever, pivoted on a stationary shaft. The lever 10 carries an adjustable weight 13, and is connected at the end of its short arm, by a tensile member 14, a steel band for example, with the short arm 16' of a lever 16 pivoted on a stationary shaft 16" and loaded by a weight 15. The lever 16 will be hereinafter referred to as the recording lever. The short arm of the recording lever is in the shape of an eccentric, upon the periphery of which the steel band 14 is secured at 14', and it is so constructed that when the recording lever rotates through equal arcs, the tensile force applied to the thread during the loading likewise increases by equal amounts, that is to say, according to a straight-line law.

The recording lever is resiliently constructed in its upper portion 17, and carries a pin 18. The part 17 may consist of a resilient strip which as shown in Figure 1 is secured at 17' to the lever 16 by rivets or the like. The upper portion 17 is secured at 17" to the lever 16 by rivets or the like. The upper portion 17 is secured at 17" to the lever 16 by rivets or the like.

can be moved against a recording device by the following means. A frame consisting of two side arms pivoted a substantial distance apart on the shaft 4 and connected by rods 20 and 42, is oscillated by a cam 19 on the shaft 1, contacted by an extension of one of the side arms. The upper portion of the recording lever 17 passes just inside the rod 20 of the frame and upon oscillation of the latter is pressed against a recording device to be described later or allowed to move out of contact therewith by its own resiliency. The recording device consists essentially of a recording cylinder 21, which is composed of individual toothed discs 22, and also of a number of slotted switching members 23 pertaining to the individual toothed discs and mounted through the slots upon a rod 23' resting in bearings in the frame of the machine, and of a diagram cylinder 24 co-operating with the recording cylinder.

Figures 2 and 3 show details of the recording means. The toothed discs 22, which are provided with teeth on part only of their peripheries, are rotatably mounted upon a shaft 25, with the interposition of discs or washers 26. The washers 26 are connected with the shaft by a projection 27 engaging in a corresponding groove or key-way in the shaft, and prevent the adjacent discs from being carried round when one toothed disc revolves. A spring 28, which presses the discs together, provides that they can only be rotated by a certain force. By means of a nut 29, which bears against the discs by means of sleeves 30 and 30', these discs can be connected fast with the shaft 25, by being pressed against the crank 33 which is likewise keyed on to the shaft 25. The sleeves 30 and 30' are supported in bearing supports 31 and 32. There is keyed on the sleeve 30', which is rotatable with the shaft 25, a toothed wheel 34 which engages in a second toothed wheel 35 mounted on a shaft 36' and connected rigidly with the diagram cylinder (24 in Fig. 1). As shown in Fig. 3, the diagram cylinder consists of two discs 37, which receive between them an india rubber cylinder 36, and which are provided with fastening members, for instance pins 38, for the diagram sheet 39, which fits over a portion of the periphery. The remainder of the periphery between the positions *a* and *b* is recessed and is of smaller radius than the part intended for the diagram. The shaft 36' of the india rubber roller is slidably supported in the bearing supports. It is subject to the action of springs 40 which draw it toward the shaft 25 and which are designed as spiral springs as shown in Fig. 3 and are secured at one end at 40' to the bearing supports while the other end engages with the shaft 36' at 40''. The toothed discs 22 and the switching members 23 occupy the position indicated in Figure 2 before the apparatus is started, so that the tooth of each switching member engages in the first gap between the teeth of the toothed disc at the position *c*. The actuating of the recording apparatus, of which for the sake of simplicity only a few toothed discs are indicated, is effected in the following manner:

In the movement of the slide 3 towards the right caused by rotation of the shaft 1 the breaking lever 10 is taken along by the pull of the piece of thread 9. Under the action of the pulling member 14, the recording lever 15, 17, with its pin 18, is therefore moved along the recording cylinder 21. When the thread breaks, the recording lever is held fast by the snapping in of a pawl 41 connected with said lever, as herein-after more fully described, and thereupon said

lever is moved by the rod 20 against the recording cylinder, so that the pin 18 displaces a corresponding switching member 23 so far that the associated toothed disc 22 is rotated to the extent of one tooth in a clockwise direction. Thereupon the rod 20, and the rod 42, described above connected with it and parallel to it, are rocked back under the action of the cam disc 19, the rod 42 bearing against the switching member 23 and sliding the latter back into its initial position. A fresh breaking test and corresponding recording may now be effected, the individual toothed discs corresponding to the breaking forces that occur being fed one tooth forward from time to time in this manner. The teeth on each disc that are fed forward constitute a measure of the frequency of the breaking force that corresponds to this disc. After the device has broken a rather large number of pieces of thread, the nut 29 is tightened up in order that the toothed discs may be pressed together, and connected with the shaft 25, and thereupon the recording cylinder is rotated by the crank 33, the diagram cylinder also being carried round with it. During this rotation the two cylinders roll over one another and all the teeth that have been fed forward on the toothed discs are pushed into the diagram sheet, as shown in Figure 4, under the action of the springs 40. The arrangement is such that the base line *b* of the diagram coincides with the point *b*, indicated in Figure 2. All the teeth that have not been fed forward, which are located before the rotation of the crank to the left of the position *c* or of the line III-III, cannot make any mark upon the diagram sheet when the crank rotates, since the two cylinders roll upon one another and the teeth that have not been fed forward only strike behind the edge *b*, that is, in the recess. According to the drawings, each toothed disc has thirty teeth. Now if it is assumed that a disc would be fed forward thirty times, the first tooth would be displaced from *c* to the position *d*. Upon rotation of the crank this tooth would first come into contact with the diagram sheet at the line 30 in Figure 4. The abscissa is divided into groups and indicates the rupture forces in grams. The scale of the diagram may of course be varied at will by adjusting or putting on weights, for instance by adjusting the weights 15 and 43.

The advantages of this diagram representation are obvious. The diagram produced shows at a glance the magnitude and the number of the minimum values that are unsafe for further treatment. The shape of the surface formed by the tooth impressions is an obvious measure of the uniformity of the yarn tested. The broader this surface is and the more peaks it shows, the less uniform is the material tested. It is important that the diagram according to Figure 4 can be produced by the apparatus according to the invention merely by rotating a crank 33, and that by rotating it a number of times the diagram can be duplicated as frequently as may be desired.

Since the mean breaking force cannot be accurately read off from the diagram there is connected with the recording lever 16, 17, a device which adds up and indicates the breaking forces occurring. For this purpose there is rotatably arranged upon the pivot of the recording lever a ratchet wheel 43, with which there engages the pawl 41, and a detent 44. The pawl 41 is rotatably mounted on a bell-crank lever 77 which

is connected at *e* to the recording lever *16* and adapted to bear against a stop *78* on the recording lever. At the commencement of the breaking operation, the recording lever moves towards the right, and at the moment when the thread breaks, the pawl *41* snaps into the ratchet wheel *43*, which is held fast by the detent *44*, and thereby prevents the recording lever from swinging back. At the end of the movement of the slide towards the left, the feeding arm *8* releases the detent *44*, and the recording lever falls back into its initial position, and in so doing rotates the ratchet wheel *43* in an anti-clockwise direction through an angle corresponding to the magnitude of the breaking force. A pointer *50* is secured to the lever *16* which moves according to the value of the breaking force. Consequently, after each stroke, the actual value of the breaking force is indicated on the corresponding scale. Rotatably mounted wheels *43* and *45* are mounted on the bearing pivot *16'* of the lever *16*. A pawl engages the wheel *43* and is connected in a special manner as hereinafter explained with the recording lever *16* so that it takes the wheel *43* with it during a movement of the lever *16* (Fig. 1) to the left. When the lever *16* returns to the initial position after each stroke (i. e. when the lever *16* moves to the left), the pawl *41* rotates the wheel *43* to the extent of the stroke. This rotation is transmitted at a reduced speed of 100 times over wheel *45*, an endless chain *46* or the like and wheels *47*, *48* to a pointer *49*. The pointer *49* continuously records on its scale the values of the breaking force. The resultant sum of all breaking forces gives the mean value if 100 tests are always made.

The mean extension is indicated in a similar manner, as hereinafter explained, through transmission elements *80* to *83* by a pointer *84*.

It is obvious that one can also work with less than 100 tests. The mean value of the breaking force or extension is then determined by a simple calculation, that is to say by dividing the indicated sums by the number of tests.

The feeding or drawing in of the thread *51'* coming from a bobbin *51* is effected by the drawing-in arm *8* by means of a clip *52*. The clip, which will hereinafter be more fully described, is closed by an abutment *53* in the left hand end position of the feed arm. In the right hand end position it is opened by a stop *54*. Figure 1 shows the drawing-in arm in the left hand end position. The thread *51'* is here seized by the clamp *52*, and, as the slide moves towards the right, is drawn into the holding clips *55* and *56* of the reaching arms *57* and *58*. These reaching arms are the long arms of angular levers mounted on the shaft *4*. The short arms of these levers rest on cams *66* and *67* mounted on the shaft *4* which thus actuates the reach arms *57* and *58*. Upon the clip *52* striking against the abutment *54* the clip is opened, and the drawing-in arm is thereupon moved back into its left hand end position for re-engagement.

Shortly before the slide reaches its left hand end position the breaking clamps *11* and *12*, which are more fully described below, are opened by means of cam discs *68* and *69* mounted on shaft *4*, the pieces of thread are brushed out of the clips by rotating brushes *61* and *62* driven by the shaft *4* as clearly shown in Fig. 1 and are conveyed to stripping devices *63*, *64*, which let the threads fall into receptacles *65*, only one of which is shown in the drawings.

The stripping device consists mainly of a sup-

port of wood or iron, on which so called stripping clothing, as is used for cards, is secured. *61* and *62* are brushes having hogs' bristles wherein the thread is caught after the rupture. The brush with the thread now passes from above, as indicated by the arrow in Fig. 1, over the stripping clothing, to which the threads adhere. Owing to the continuous downward movement of the brushes, the threads are finally wound into balls and occasionally drop down from the clothing in lumps.

As soon as the broken pieces of thread have been removed from the rupture clips, the fresh piece of thread already drawn in, is placed in the open breaking clips by a rocking movement of the reaching arms *57* and *58*, effected by means of the cams *66* and *67*, and shortly afterwards the clips close.

It is important that the drawing of the thread into the reaching arms *57* and *58* should occur simultaneously with the breaking of the piece of thread *9* already clamped in the breaking clips *11* and *12*.

This special arrangement, and also the circumstance that the apparatus is driven continuously and uniformly, and consequently permits of a comparatively high speed of the breaking clips *11* and *12*, which is not hindered by the damping means usual in other apparatus, enable the number of breaking tests per unit of time to be made much greater in practice than has hitherto been possible.

The collecting device indicated by *61*, *62*, *63* and *64* for the broken pieces of thread is provided for the purpose of determining the yarn count by weighing these pieces. Hereby a valuable check upon the count of yarn is rendered possible. Furthermore the percentage of water in the broken threads can be determined, and this, as is known, considerably influences the ultimate strength of the thread.

In order to cut off the thread after it has been drawn in, there is provided upon the shaft *4* a cam disc *68'* which actuates a pair of shears *68*. From Figure 5 the construction and the co-operation of the clips can be seen.

The clip *52* consists of two clamping members *87* and *88*, which are rotatably arranged upon a bolt or pin *86* mounted on the lever *8*, and are held together by a spring *90*. In the bolt *86* is inserted a little pin *91*, which in its turn runs in a groove *92* in the clamping member *88*. When the clamp member *88* strikes with its extension *89* against the abutment *54*, shown in Figure 1, the clip opens, that is to say, the member *88* moves away from the member *87* until the little pin *91* enters the end *93* of the groove *92*, which is perpendicular to the bolt *86*. The little pin can therefore no longer snap back, notwithstanding the opposing force of the spring *90*. Again when the clamp member strikes the abutment *53* (Fig. 1) the clamping member *88* then undergoes an opposite movement.

The spring comes into action, and the thread *51'* is nipped, and is pulled by the drawing-in arm *8* into the funnel-shaped clamps of the reaching arms *57*, *58*. The thread is held fast between the end *94* of the reaching arm and the member *86* loaded by a weak spring *95*. The reaching arms *57* and *58*, controlled by the cam discs *66*, *67*, convey the thread towards the rupture clamps *12* and *11*. These are mounted one on the end of the rupture lever *10* and one on the slide *3*. Their structure and operation is shown in Fig. 5. The relatively stationary element *96*

of each forms a clamp with the movable piece 97, which clamp is held closed by a spring 99 and opened by a cam 59 or 60 mounted on the shaft 1.

As the reaching arms deliver the thread to the rupture clamps the eccentrics 59 and 60 come into contact with the clamping pieces 97 and open the clamp. Due to rotation of the eccentrics however, the pressure upon the clamping piece 97 ceases, a spring 99 pulls it back into the original position, and the thread is now firmly clamped.

Since in the testing of yarns in general the extension is also ascertained, there is provided for this purpose a device which determines and indicates the sum of the extensions. This device consists of a pawl 69, which is mounted on the rupture lever, and which engages in a ratchet wheel 70 arranged upon the pivot of the rupture lever, a toothed wheel 71 arranged beside the ratchet wheel, with a pawl 72, and a toothed rack 73, which co-operates with the toothed wheel, and which is pulled by a spring 74 and held by a stationary detent 75. A further pawl 76 on the slide 3, which can likewise engage in the rack 73 and a bell-crank lever 77 pivoted to the recording lever 16 at e and carrying the detent 41, are provided for the device for measuring the extensions.

For measuring the extensions two different magnitudes are ascertained, namely the stroke of the rupture lever clip 12 and the residual stroke traversed after the breakage of the thread by the rupture clip 11 on the slide. The sum of these two magnitudes is equal to the difference between the total slide stroke and the extension of the thread. These magnitudes are indicated in the following manner:

Upon breakage of the thread the lever 16 has a tendency to return to its initial position under the action of the weight 15. This is, however, prevented by the dropping of the pawl 41, which is mounted on the bell-crank lever 77, into the wheel 43 secured by the pawl 44. Since the long arm of the bell-crank lever bears during the breaking movement of the carriage through gravity on the pawl 76 and the short arm of the bell-crank lever does not therefore come in contact with the stop 78, the bell-crank lever is swung about the pivot e until its short arm bears on the stop 78. By this swinging movement the long arm of the bell-crank lever, which normally holds the pawl 76 out of engagement, is raised so far that the pawl 76 drops into the rack 73 and the latter is therefore moved towards the right through the residual stroke of the slide. During this movement the toothed wheel 71, with the pawl 72, is moved in a clockwise direction, and the spring 74 is stressed, the pawl 75 preventing the rack 73 from slipping back. Upon the return of the slide 3 its end portion 79 releases the pawl 75, so that under the action of the spring 74 the ratchet wheel 70 is rotated, and by means of a pawl 72 the ratchet wheel 70 is also rotated. A pointer 84 connected with the ratchet wheel 70 through the transmission elements 80, 81, 82 and 83 therefore indicates first the residual stroke of the rupture clamp 11. Previously, however, the ratchet wheel 70, after the breakage of the thread, when the rupture lever 16 falls back, is rotated by the pawl 69 through an angle which corresponds to the stroke of the rupture clamp 12. This stroke also is likewise indicated by the pointer 84. Now when 100 lengths of thread are tested, the distance between f and g on the scale for pointer 84 is made to correspond to 100 entire strokes of

the slide 3. Then the part of the scale to be read between the scale mark g and the tip of the pointer represents the total extension, so that here again in one hundred measurements the mean value, that is to say, the mean extension, is indicated.

The entire apparatus described above indicates the important test values in an entirely automatic manner, and only a zero testing of the indicating device or a zero reading is required, and, after the apparatus has been working automatically for some time, a rotation of the crank 33 for the production of the diagram, and a reading of indicating appliances, are necessary. In order that the operator may secure information concerning the number of pieces of thread already broken, and concerning the number of pieces still to be tested, a counting device is provided, consisting of an abutment 85 on the slide, and a lever 86 actuated thereby, with a feed pawl or detent 87, a ratchet wheel 88 and a pointer 89. A spring 100 is also provided for drawing the arm 86 into its starting position which may be limited by a fixed abutment 101.

The recording device according to the invention is not restricted to the use in machines for testing yarns but may also be employed for other purposes, for example, in cases wherein frequency operations are to be recorded.

What I claim is:—

1. In a machine for testing the tensile strength uniformity of threads of definite length, a recording device for indicating the strength values of the threads in order of magnitude and recurrence frequency comprising a row of counting members arranged in juxtaposition, a lever, means for positioning said lever successively along said row in accordance with the tensile strength of each piece of thread, and means causing said lever after the breakage of each thread to advance a unit distance the feed of that counting member which corresponds in its position to the position of said lever.

2. In a machine for testing the tensile strength uniformity of successive pieces of thread of definite length, a recording device for indicating the strength values of the threads in order of magnitude and recurrence frequency comprising a row of counting members arranged in juxtaposition, a feeding means for each counting member, a lever, means for positioning said lever successively along said row in accordance with the tensile strength of each piece of thread, means to move the lever into contact with a feeding means to advance the corresponding counting member at the termination of the test of each piece of thread, and a diagram marking device connected with the recording device.

3. In a machine for testing the tensile strength uniformity of successive pieces of thread of definite length, a recording device for indicating the strength values of the threads in order of magnitude and recurrence frequency comprising a row of rotatable toothed discs forming a roller, a feeding means for each disc, a lever, means for positioning said lever successively with its end portion along the toothed disc roller in accordance with the tensile strength of each piece of thread, means to move the lever into contact with a feeding means to advance the corresponding toothed disc at the termination of the test of each piece of thread, and a diagram marking device connected with the recording device.

4. In a machine for testing the tensile strength uniformity of successive pieces of thread of a definite length by means of a weight loaded rup-

ture lever carrying a thread clamp, a recording device for indicating the strength values of the threads in order of magnitude and recurrence frequency comprising a row of counting members 5 arranged in juxtaposition, a recording lever, means for positioning said recording lever successively along said row in accordance with the tensile strength of each piece of thread, and a pulling member connecting the recording lever 10 with the said rupture lever.

5. The device as claimed in claim 4, in which the recording lever has an extension of eccentric shape serving for the fixing of the pulling member thereto.

15. 6. In a machine for testing the tensile strength uniformity of successive pieces of thread of a definite length, a recording device for indicating the strength rupture values of the threads in order of magnitude and recurrence frequency, comprising a row of toothed discs forming a roller, 20 a lever, means for positioning said lever successively along said toothed disc roller in accordance with the tensile strength of each piece of thread, a feeding means comprising a row of 25 pawls engaging in the toothed discs and two jointly rockable feeding rods parallel to the toothed disc roller, adapted to press the recording lever against a pawl to feed the corresponding toothed disc and to subsequently return the 30 pawl to its initial position.

7. In a machine for testing the tensile strength uniformity of pieces of thread of a definite length, a recording device for indicating the strength values of the threads in order of magnitude and 35 recurrence frequency comprising a row of rotatable toothed discs toothed only upon a portion of their periphery, a recording lever, means for successively positioning said lever along said row in accordance with the tensile strength of each 40 piece of thread, means causing said lever after breakage of each thread to rotate the corresponding disc a unit amount, a rotatable shaft and crank for the toothed discs, means for connecting the toothed discs fast to the shaft and a 45 cylinder for carrying a diagram sheet thereon, and means for rotating this cylinder and the toothed discs in unison for the purpose of pressing the teeth of the toothed discs which have been advanced by said recording lever into the 50 diagram sheet.

8. In a machine for testing the tensile strength uniformity of pieces of thread of a definite length, a recording device for indicating the strength values of the threads in order of magnitude and 55 recurrence frequency comprising a row of rotatable toothed discs toothed only upon a portion of their peripheries, a recording lever, means for successively positioning said lever along said row in accordance with the tensile strength of 60 each piece of thread, means causing said lever after breakage of each thread to rotate the corresponding disc a unit amount, a rotatable shaft and crank for the toothed discs, coupling discs on the rotatable shaft between the toothed discs, a clamping nut on the end of the shaft for pressing the toothed discs and coupling discs together, and a cylinder for carrying the diagram sheet, 65 said last named cylinder being adapted to be rotated with the toothed discs for the purpose of pressing the teeth of the toothed discs which

have been advanced by said recording lever into the diagram sheet.

9. In a machine for testing the strength uniformity of successive pieces of thread of a definite length, a recording device for arranging the tensile strength values of the threads in order of magnitude and frequency comprising a row of counting members arranged in juxtaposition, a weight loaded recording lever, means for positioning said lever successively along said row in 10 accordance with the tensile strength of each piece of thread, and means causing said lever after the breakage of each thread to rotate the corresponding counting member a unit amount, and an indicating device comprising a ratchet 15 wheel upon the pivot of said recording lever, said indicating device being driven by the ratchet wheel by the aid of a transmission and a detent on the recording lever engaging the ratchet wheel and adapted to advance the ratchet wheel 20 when the recording lever falls back after breakage of a thread.

10. In a machine for testing the tensile strength uniformity of successive pieces of thread of definite length, a reciprocating slide, a test 25 clamp thereon, a weight-loaded test lever carrying a second test clamp, two rockable reaching arms with holding clamps at the ends, and a drawing-in arm connected with and movable by the slide, the drawing-in arm being adapted with 30 the testing movement of the slide to draw in a piece of thread so that the rupture of a piece of thread and the drawing-in of a new piece of thread into the holding clamps of the reaching arms take place simultaneously. 35

11. In a machine for testing the tensile strength uniformity of successive pieces of thread of definite length, a reciprocating slide, a test clamp on the slide, a weight-loaded test lever, a second test clamp carried by the test 40 lever, two rockable reaching arms, holding clamps at the ends of the reaching arms, a rockable drawing-in arm for the simultaneous drawing in of a new piece of thread during the testing movement of the slide, a tension rod connecting the drawing-in arm with the slide, a thread clamp at the end of the drawing-in arm, and stationary abutments at the ends of the stroke of the drawing-in arm in the path 45 of the thread clamp for opening and closing this 50 clamp.

12. In a machine for testing the tensile strength uniformity of successive pieces of thread of definite length, a reciprocating slide, a test clamp on the slide, a weight-loaded testing lever mounted to cooperate with said slide, a second test clamp carried by the testing lever holding the thread during the testing movement of the slide, two rockable reaching arms, a drawing-in arm connected with the slide, the drawing-in arm being adapted, during the testing of one piece of thread, to draw a fresh piece of thread into the holding clamps of the reaching arms, a driving shaft, and a plurality of cam discs arranged on the driving shaft to control the testing clamps and reaching arms, and a cutting device for cutting off the piece of thread to be tested. 60 65

JOHANN PAUL LAETSCH.
